INSULATED RAILWAY TRACK CONSTRUCTION

Filed June 20, 1931

UNITED STATES PATENT OFFICE

BRUNO E. BALDUF, OF CHICAGO, ILLINOIS, ASSIGNOR TO UNITED STATES GYPSUM COMPANY, OF CHICAGO, ILLINOIS, A CORPORATION OF ILLINOIS

INSULATED RAILWAY TRACK CONSTRUCTION

Application filed June 20, 1931. Serial No. 545,705.

This invention relates to railway track constructions, and has reference more particularly to track constructions in which the rails are resiliently supported by springs to avoid transmitting vibration to the rail supporting framework and thus decrease the amount of noise produced by the train.

In my Patent 1,811,250 on June 23, 1931, I have described the type of spring clip for reducing sound caused by sound waves or impact vibrations and I find that this type of clip is especially advantageous in railway constructions for supporting the track and preventing vibrations from being transferred to the supporting railroad base or framework. The sound insulation of railway tracks is especially important in thickly populated districts where elevated or surface tracks are used, and it is also important in subways where the sound produced by the passing trains are reverberated and are often of such volume as to cause discomfort to the rider in the train.

An object of this invention, therefore, is to provide a construction suitable for supporting the rails of railroads so as to reduce the sounds and vibrations produced by passing trains.

Another object of the invention is to provide a resilient support for railroad rails to prevent the vibration of the road bed or framework supporting the rails.

A further object of the invention is to provide a resilient construction for supporting railway rails which will be economical to manufacture and install; also to improve railway constructions in other respects hereinafter specified and claimed.

Reference is to be had to the accompanying drawings forming a part of this specification, in which

Fig. 1 is a sectional elevation through my improved railway construction showing the application of the spring clips for supporting the rails,

Fig. 2 is a plan view showing one of my resilient bases or units under a rail,

Fig. 3 is a sectional elevation through the railway construction taken on line 3—3 of Fig. 1,

Fig. 4 is a sectional elevation through a modified form of the railway construction,

Fig. 5 is a plan view of the construction shown in Fig. 4,

Fig. 6 is a sectional elevation through the modified construction taken on line 6—6 of Fig. 4, and

Fig. 7 is a perspective view of one of the multiple leaf spring clips which I prefer to use in the railway construction.

Fig. 8 is a modified form of spring clip.

In carrying out my invention, I preferably utilize a number of spring clips as described in said Patent 1,811,250 superposed one on the other and secured together at their central saddle portion 10 and at their two ends 11 as by spot-welding, riveting, bolting or the like. Integral loops 12 connect the saddle members 10 to the clip ends 11, said loops being arranged to first extend upwardly at an angle 70 to the vertical from the saddle member 10, curve in arcuate form, and then extend downwardly at an angle to the vertical to form legs 13 which are integrally connected with the inner edges of the clip ends 11. In assembling several of the clips to form a multiple leaf spring, using say three clips as shown in Fig. 7, the arcuate sections 12 are preferably spaced slightly apart so that they can act independently of each other and thus produce a somewhat superior effect from a sound and vibration reducing standpoint. By spacing the loops 12 apart, they can also deflect independently of each other without friction contact and thus eliminate the necessity of oiling between the springs. By utilizing the multiple leaf springs, I can support very heavy loads in the form of railway trains, and still arrange my spring clips over a comparatively

50

60

65

75

80

85

90

small area, thus materially reducing the installation cost.

Any number of the multiple leaf springs may be assembled to form a unit having the desired resiliency and deflection under a given load. For example, in Figs. 1 and 2, I have shown one of these units as composed of twelve of these multiple leaf springs which are secured to a plate 15 by spot-welding or by other suitable means. The plate 15 is preferably rectangular in shape and three of its edges are provided with bevels 16 to be received inside of upwardly tapered flanges 17 formed along three sides of a similar holding plate 18. The fourth edge of the plate 18 extends somewhat beyond the base plate 15 and is provided with a plurality of brackets 19 held down by tap bolts 20 for retaining the plate 15 in position on the plate 18. A suitable shoulder 21 is formed on the bracket 19 for preventing displacement of the plate 15 inwardly as seen in Fig. 1. Asphalt emulsion 22 or other suitable waterproofing agent may be used between the plates 15 and 18 to prevent rusting thereof and to secure said plates together. The plate 18 is supported by a masonry pit 23, being secured thereto by grouting material 24 which is adapted to give a uniform contact of the plate 18 on the pit 23 at all times. The pit 23 has a central gutter 25 between the rails 26, and has upstanding walls 27 at each side, one of which may be used to support the third rail 28 which is commonly used for electric railways.

The spring clips are preferably arranged on the plate 15 in rows (Figs. 1 and 2) of any desired number such as three, each row containing four clips making 12 clips to a unit. Each row of spring clips has its saddle members 10 in alignment for receiving parallel ribs 30 which may be of bar steel and supported at their upper edges by transversely extending grid bars 31, also of bar steel and welded to the bars 30. A plate 32 may extend over the bars 31 and be provided with downwardly extending flanges 32 on each edge. The bars 31 are preferably rigidly secured to the plate 32 and steel blocks 34 are secured to the upper face of the plate 32 as by bolts 35. A pair of blocks 34 is used, and the space between is partially filled with a wooden block 36 upon which the base 37 of rail 26 rests. Clamps 38 are secured by bolts 39 to each of the blocks 34 and bear on the upper surface of the rail base 37 to hold said rail firmly in position on the wooden block 36.

Gusset plates 40 are secured to the upper face of plate 32 and extend outwardly therefrom to be attached to a tie truss 42 which may be composed of two angles back to back said truss being secured to the plate 40 as by bolts 43, rivets or the like. The truss 42 thus connects the two resilient units supporting each of the rails 26 and acts to ac-

curately space the rails 26 the desired distance apart to fit the wheels of the railway train. In order to prevent any material side-play of the rails 26 under the action of a moving railway train, I provide auxiliary springs 45 of the same shape as the multiple leaf spring heretofore described. These springs 45 are preferably arranged in a row and secured to an upstanding bracket or flange 46, secured to each end of the plate 15. A bar 47 is secured across the aligned saddles of spring 45 and extends slightly beyond the loops 12 to engage a slide or bearing bar 48 secured to the inside lower surface of each of the flanges 33. As the main spring clips then deflect, bar 47 slides along the face of the block 48, while any side-play tendency of the rails 26 is prevented by the lateral thrust of the blocks 47 onto the bar 48. A packing strip 49 of asphalt soaked fibers or other suitable material, is preferably provided in the space between the outer-most flange 33 and its adjoining masonry ledge 27 so as to prevent any dirt or water from getting into the space occupied by the spring 90 clips. A filling material 50 of oil or asphalt impregnated fibrous material of low density is also preferably placed in the space around the spring clips so as to keep said clips lubricated and to also prevent any drum action 95 due to sounds reverberating in the space around the clips.

In the modified form of the invention shown in Figs. 4, 5, and 6, the construction above the plate 32a is preferably altered in 100 that a short wooden block 52 of about the cross-sectional area of an ordinary railway tie, rests on said plate 32a and is secured thereto by upstanding plates 53 which are welded to the downstanding flanges 33a 105 formed around the outside periphery of a plate 32a. Inwardly extending flanges 53a are formed along the top edge of plates 53 and extend into registering slots in the blocks 52 so as to permit the removal and 110 replacement of said blocks at intervals. A metal rail bracket 53b is supported on each of the wooden blocks 52, being provided on its upper surface by a recess 54 for receiving the base 37 of the rail. Spikes 55 are then passed through openings in the bracket 53 and connect the rail base 37 to said block 52. A tie bar 56, extends between the rails 26 and has a hook 57 on each end adapted to receive the outside edge of rail base 37. A bar 58 is secured by bolts 59 near each end of the tie bar 56, and has an offset end 60 for engaging the opposite edge of the rail base 37.

In the type of modified spring clip shown in Fig. 8, the saddle member 61 is formed at each of its ends into a pair of spring loops 62 and 63 terminating in clip ends 64 which may extend perpendicularly to the saddle member 61 and be attached to the upstand-

ing legs of a supporting channel not shown. Through the use of this type of clip, the upper plates 32 or 32a may be connected directly to said saddle members 61, thus eliminating the necessity of the ribs 30 and 31.

5 I would state in conclusion, that while the illustrated examples constitute practical embodiments of my invention, I do not wish to limit myself precisely to these details, since 10 manifestly, the same may be considerably varied without departing from the spirit of the invention as defined in the appended claims.

Having thus described my invention, I claim as new, and desire to secure by Letters

15 Patent:—

1. In a resilient rail construction, a unit plate, a plurality of flat spring clips secured to said plate, each of said clips having a central, integral saddle member, and a rail 20 plate secured to said saddle members to form a resilient support for a rail so as to induce vibrations of said unit plate by the passage of a train along said rail.

2. In a resilient rail construction, a unit 25 plate, a plurality of flat, spring clips secured to said plate, each of said clips having a central, integral saddle member, a rail plate secured to said saddle members to form a resilient support for a rail, and a material of low 30 density positioned around said spring clips to keep out dirt and prevent drum action between said plates.

3. In a resilient rail construction, a pair of 35 plates in spaced, parallel relation, a rail supported by one of said plates, flat, spring clips between said plates and having central, integral, saddle members secured to one of said plates and outstanding ends in a different 40 plane than said saddle members and secured to the other of said plates, and integral, ar- cuate loops connecting said clip ends and saddle members.

4. In a resilient rail construction, a pair of 45 supporting elements in spaced, parallel relation, a rail supported by one of said elements, and spring clips having portions thereof secured to each of said elements, said clips comprising a plurality of superimposed, independently acting leaves.

5. In a resilient rail construction, a pair of 50 supporting elements in spaced relation, a rail supported by one of said elements, spring clips having portions thereof secured to each of said elements to permit vertical, 55 relative movement of said elements, and auxiliary spring clips associated with said rail supporting element to permit limited, yielding, lateral movement of said rail supporting element.

6. In a resilient rail construction, a pair of 60 supporting elements arranged in a substantially horizontal plane, a rail supported on each of said elements in spaced, parallel relation, a plurality of flat spring clips below 65 each of said elements and secured thereto,

said clips having integral saddle sections and ends in different planes, a base element supporting said clips, and a tie element connecting said rail supporting elements.

7. In a resilient rail construction, a pair 70 of plates in spaced, parallel relation, a plurality of stiffening ribs secured to the lower face of the upper of said plates, a plurality of flat, spring clips having central, integral saddle sections secured to said ribs, and integral, outstanding legs on said clips in a plane different than said saddle sections, said clip ends being secured to the lowermost of said plates.

8. In a resilient rail construction, a pair of 80 plates in spaced, parallel relation, a rail supported on the upper of said plates, flat spring clips secured to the inside faces of said plates to permit vertical movement of the upper plate relative to the lower plate, 85 said clips being arranged to permit lateral movement in one direction only of the upper plate relative to the lower plate, and auxiliary spring clips associated with said plates and arranged to yieldingly limit the lateral 90 movement of the upper plate relative to the lower plate.

9. In a resilient rail construction, a pair 95 of plates in spaced, parallel relation, a rail supported on the upper of said plates, flat spring clips secured to the inside faces of the said plates to permit vertical movement of the upper plate relative to the lower plate, said clips being arranged to permit lateral movement in one direction only of the upper 100 plate relative to the lower plate, telescoping, inwardly extending flanges formed on opposite edges of said plates, and auxiliary spring clips between said flanges and arranged to yieldingly limit the lateral movement of the 105 upper plate relative to the lower plate.

10. In a resilient rail construction, a pair 110 of spaced, parallel plates, flat spring clips yieldingly connecting said plates, a rail supported by the upper of said plates, a base plate for supporting the lower of said plates, retaining flanges formed on a plurality of edges of said base plate, and clamping means for locking said lower plate between the flanges of said base plate.

11. In a resilient rail construction, an 115 elongated masonry road bed having upstanding flanges along each edge thereof, a plurality of flat spring clips supported by said road bed, a plate yieldingly supported by said clips, a rail supported by said plate, and packing material between said plate and said road bed flanges for preventing the passage of dirt into the space around said clips.

12. In a resilient rail construction, an 120 elongated road bed, a plurality of flat spring clips supported by said road bed, a plate yieldingly supported by said spring clips, a block of wood supported by said plate, and a rail supported by said block of wood.

13. In a resilient rail construction, a pair of supporting elements in spaced relation, a rail supported by one of said elements, a base for supporting the other of said elements, flat, spring clips between said elements having central, integral, saddle members supporting one of said support elements, spring ends in a different plane than said saddle members and supported by the other of said support elements, and integral, arcuate loops connecting said clip ends and saddle members so as to form a resilient support for said rail and so as to reduce vibrations of said base by the passage of a train along said rail.

CERTIFICATE OF CORRECTION.

Patent No. 1,855,177.

April 26, 1932.

BRUNO E. BALDUF.

It is hereby certified that error appears in the printed specification of the above numbered patent requiring correction as follows: Page 1, line 11, after the word "vibrations" insert a comma; page 3, line 21, claim 1, for "induce" read reduce; and that the said Letters Patent should be read with these corrections therein that the same may conform to the record of the case in the Patent Office.

Signed and sealed this 5th day of July, A. D. 1932.
